ATTY'S.

UNITED STATES PATENT OFFICE.

THOMAS G. MOUAT, OF CLEVELAND, OHIO.

VALVE.

1,104,918.

Specification of Letters Patent. Patented July 28, 1914.

Application filed September 25, 1913. Serial No. 791,682.

To all whom it may concern:

Be it known that I, THOMAS G. MOUAT, a citizen of the United States, residing at Cleveland, in the county of Cuyahoga and State of Ohio, have invented a certain new and useful Improvement in Valves, of which the following is a full, clear, and exact description, reference being had to the accompanying drawings.

10 This invention relates to valves, and has particular reference to a valve for use in connection with vapor heating systems, although it will be obvious that the same may be employed for many other purposes. 15 However, its use in connection with vapor heating systems presents certain advantages over other valves heretofore employed, owing to the desirability of obtaining an accurate adjustment necessitated by the 20 smallness of the pressures employed.

It has long been customary to provide the spindles of turning plug valves with pointers or projections which shall not only indicate at all times the position of the valve, 25 but shall also, by coöperation with stops carried by the valve casing, limit the rotation of the plug in one or both directions. Heretofore it has frequently been customary to make one or the other of these stops in the 30 form of an adjustable stud suitably secured to a flange or ledge carried by the valve casing, so as to permit the plumber or steam fitter or other skilled person to adjust the swing of the valve to the amount necessary 35 for the proper operation of the devices connected therewith. The further adjustment of these studs, has, however, been such an easy and obvious matter as to cause the users to shift the same in an attempt to obtain 40 more heat or otherwise to modify the action of the apparatus with the result that the beneficial results of the first adjustment have been lost, and the apparatus caused to operate unsatisfactorily.

45 It is therefore the main object of this invention to provide a device of this character in which the mode of adjustment shall not be apparent to the layman, although an easy and simple matter for the person who is acquainted therewith; the provision of a device of this character wherein the stop member, in whatever of its adjusted positions it may be located, shall appear to be at the extreme limit of its movement so as not to induce the user to believe that further opening 50 is possible; the provision of a device

in which the adjusting and securing parts are concealed from view; the provision of a valve device in which the positions of handle and stop may be varied as regards each other, and the valve itself; while further objects and advantages of the invention will become apparent as the description proceeds.

Generally speaking, my invention may be defined as consisting of the combinations and constructions recited in the claims here-to annexed and illustrated in the drawings accompanying and forming a part of this application wherein—

Figure 1 is a side elevation of the complete 70 valve construction in accordance with my invention; Fig. 2 is a vertical, cross-sectional view through the same taken upon the line 2—2 of Figs. 1 and 3; Fig. 3 is a plan view of the valve shown in Fig. 1; Fig. 4 is a plan 75 view of the same valve, the handle and adjustable stop being omitted; Fig. 5 is a detailed perspective showing the separate parts, of the handle and adjustable stop in separated position; and Fig. 6 is a vertical, cross- 80 sectional view through a modified form of device.

Describing the parts by reference characters, 1 represents the body or casing of the valve, which is formed with suitable inlet 85 and outlet nipples 2—2, disposed in any convenient manner and formed between these nipples with a suitable seat for the movable valve member 3. Secured to this movable valve member is a rotatable stem 4, journaled within a suitable aperture 5 which is formed in the wall of the body or casing, the latter being here provided with a hollow extension 6, spaced from the valve stem and 90 interiorly threaded as at 7, for the reception 95 of a gland nut 8, whereby suitable packing 9 may be pressed around the stem as in the usual valve construction. The exterior of the extension 6 is preferably made of cylindrical form, as shown in Figs. 2 and 4, for 100 a purpose to be described hereafter, the nut 8 being sunk therein for its entire thickness in the embodiment shown in Figs. 1 to 4, inclusive.

Carried by the casing or body 1 at the 105 foot of the extension 6 is a laterally projecting ledge or flange 10, preferably having a fixed stop 11, whereby the closing movement of the valve may be limited, and also, in the present embodiment, having a circularly arranged series of recesses 12—12, these recesses preferably terminating short of the

lower face of the ledge or flange, as shown in Fig. 2, so as not to be visible from beneath the same. Mounted upon this flange is an. 5 adjustable stop member consisting of a flat, segmental metal plate 14 having its inner portion extended to form an integral ring 15 which is adapted to surround the extension 6, so as to maintain the plate 14 in engagement with the ledge or flange. The 10 outer edge of the plate 14 preferably coincides with the edge of the ledge or flange 10 and the lower face of the same is provided with a stud 16, adapted to enter any one of the recesses 12 so as to maintain the 15 plate in any adjusted position and secure it against shifting. The angular extension of the plate 14 should be equal to the range of the adjustment desired so that the plate may cover all of the recesses which are to the 20 rear of the one in use, while the forward extremity of the plate is preferably provided with some indication, such as the word "open", to lead the users to the belief that the valve is actually wide open when the indicator arrives at this point.

The projecting end of the stem is squared or flattened as at 18 for the reception of the member 19 which is provided, at one side, with the down-turned finger 20 whose end 30 projects in proximity with the ledge or flange 10 so as to engage the fixed and movable stops. To the flattened portion of the stem, above the member 19, is attached the operating handle 21, the same being preferably 35 separate from the member 19 so as to permit it to be shifted to different positions as required by the proximity of the walls, pipes and other obstructions. The handle 21 and member 19 are secured to the stem in 40 any convenient manner, as by the screw 22.

In order to conceal the movable character of the ring 15 and also to hold this ring sufficiently tight to the face of the ledge or flange 10, I cover and surround the extension 6 with a suitable cap, the same (in Figs. 1 to 5) comprising a cylindrical wall or hollow member 24 surmounted by an apertured end-closure 25 which is adapted to surround the stem and overlie the gland nut 8. In this case the various parts can be 45 dismounted so as to permit the adjustment of the movable stop merely by removing the screw 22.

In the embodiment shown in Fig. 6, the 55 exterior of the extension 6^a is shown as threaded for the reception of the member 24^a which, in this case, preferably terminates flush with the outer end of the extension, the gland nut 8^a being provided with a peripheral flange 26 overlying this member and concealing its movable character. In 60 this modification, the greater difficulty of dismounting the parts shields the adjustment yet further from derangement at the 65 hands of unskilled persons.

While I have described my invention in detail, I have done so from the fact that the constructions here disclosed have been proven by experience to be particularly suited to the end in view. However, I do not propose to be limited to such details except as the same may be positively included in the claims hereto annexed or may be rendered necessary by the prior state of the art.

Having thus described my invention, what I claim is:—

1. In an adjusting valve, the combination, with a casing and a rotatable stem carried thereby, said casing having a hollow threaded extension surrounding said stem provided with a packing gland, and also having an exterior surface of revolution substantially concentric with said stem, of an adjustable member surrounding said extension and having a surface of revolution complementary to said first surface, there being a plurality of recesses in one of said surfaces and a projection extending beyond the other surface adapted to enter any one of said recesses, the angular extent of each of said surfaces being sufficient to cause more or less of the said recesses to be hidden, a projecting part movable with said stem and arranged to engage a portion of said adjustable member whereby the angular movement of said stem may be limited, and means surrounding said extension and engaging said adjustable member, whereby it is held against said first surface and the fact of its adjustability is concealed.

2. In a device of the character described, the combination with a valve casing and a rotatable stem carried thereby, said casing having a ledge surrounding said stem and provided with an arcuate series of recesses, of a movable stop member surrounding said stem and having a segmental portion adapted to overlie and conceal more or less of the said recesses, a stud carried by the lower face of the said stop member and adapted to enter any one of the said recesses to fix the position of the said stop member, means carried by said casing for clamping said stop member against said ledge and a projecting part movable with said stem and arranged to engage a portion of said stop member whereby the angular movement of said stem is limited.

3. In a device of the character described, the combination with a valve casing and a rotatable stem carried thereby, said casing having a substantially cylindrical extension surrounding said stem; of an integral projection surrounding said extension and formed as a surface of revolution concentric with said stem, said projection having in its face a plurality of recesses arranged about said extension, a ring surrounding said extension and lying against the face of said

projection, a segmental plate integral with said ring and adapted to overlie and conceal more or less of said recesses, a stud carried by the face of said plate and adapted to enter any one of the said recesses whereby the position of the said plate may be determined, a hollow member surrounding said extension and resting upon said ring, a finger rigid with said stem and adapted to

engage a portion of said plate, and means for securing said hollow member in place upon said extension.

In testimony whereof, I hereunto affix my signature in the presence of two witnesses.

THOMAS G. MOUAT.
